UNITED STATES PATENT OFFICE.

OSCAR FALKENWALDE, OF BALTIMORE, MARYLAND, ASSIGNOR OF ONE-HALF TO CHARLES F. STAUFFEN, OF BALTIMORE, MARYLAND.

HYDROCARBON-BURNER.

SPECIFICATION forming part of Letters Patent No. 742,777, dated October 27, 1903.

Application filed November 21, 1902. Serial No. 132,278. (No model.)

To all whom it may concern:

Be it known that I, OSCAR FALKENWALDE, residing in the city of Baltimore and State of Maryland, have invented certain new and useful Improvements in Hydrocarbon-Burners, of which the following is a specification.

My invention, which in its general nature relates to improvements in hydrocarbon or gaseous-fuel burners, is more especially designed for use in connection with that type of burners now utilized for domestic purposes in cooking-ranges and heating-stoves and in which ordinary kerosene-oil is the fuel used.

In the practical application of the type of coal-oil burners referred to it has been found that the decomposition of the gaseous vapor of the coal-oil is more or less incomplete, and by reason thereof considerable difficulty is found to obtain the desired heating-flame quality of the burners. Furthermore, the incomplete combustion of the oil causes a too rapid consumption of the fuel and the consequent waste of heat by reason of an improper mixture of oxygen with the gaseous vapor and also the carbonizing of the burner and the stove with incrustations or deposits, and particularly creates a disagreeable blowing noise.

The above and other objections, hereinafter referred to, I seek to overcome by my present invention, which generically comprehends a slow or drip feeding means for conveying water into a discharging-nozzle supported outside the hot zone of the burner, whereby to but partly convert the water into a moist vapor and for discharging the water in a direction crossing through beside or below the flow of the gaseous-vapor discharge from the burner needle-valve or ejector to intermix with the said gaseous vapor.

In its more subordinate features my present invention embodies certain arrangement and peculiar combination of parts, all of which will hereinafter be fully explained, and specifically pointed out in the appended claims, reference being had to the accompanying drawings, in which—

Figure 1 is a perspective view of an oil-burner equipped with my present invention. Fig. 2 is a longitudinal section thereof. Fig.

3 is a view of my water-dripping attachment separated from the burner.

In the drawings I have illustrated my present invention as applied to the special form of oil-burner which is fully disclosed in and forms the subject-matter of my copending application, Serial No. 122,891, and while my present improvements are especially designed for use with the said form of burner I desire it understood that the same in its generic nature is arranged to be used in connection with any other form of oil-burner in which the gaseous fuel is ejected into a retort or combustion-chamber.

The burner shown comprises a body or casting 1, having a series of transversely-arranged flues *b*, that extend entirely across the casting 1, and said flues *b* are bisected by a central longitudinal bore or flue *a*, which extends from the straight end *x* of the casting 1 to the tapered end *1°*, as clearly shown in Fig. 2, and at the tapered end the bore *a* is forked and extends divergently outward to form two oppositely-extended discharges *a' a'*.

c c designate a series of air-flues that extend through the bottom of the retort and communicate with the flues *b*, and *c'* is a smaller air-flue that joins with the central flue or bore *a*.

2 designates a supporting-base having side and end flanges and provided with a series of longitudinal pockets to receive an absorbent body 3, it also having a series of air-slits *2×*, which extend the length of the said base and through which air is fed under the retort, the latter being supported sufficiently above the slits *2×* to permit of a proper circulation of air under the retort and in the air-flues *c c'*. At one end the base 2 is extended, as at *2a*, and on the said extension is mounted an absorbent *2b*, which is disposed directly under the needle-valve or fuel-ejector *g* to collect the drippings therefrom.

F designates a feed-pipe which connects with the source of oil-supply, and the said pipe joins with an inside asbestos-covered generator-pipe *G*, that extends up in front of the tapered end of the casting 1 between the flues *a' a'* and connects at the upper end with a horizontal section *G'*, supported over the top

of the casting 1, but not in direct contact therewith. At the rear end generator-pipe section G' has a pendent member g, which terminates in a valve-chamber g' to receive the 5 needle-valve or ejector devices g², of any well-known construction and arranged to discharge the fluid or vaporized fuel into the bore or main flue of the casting 1.

In the form of burner as described in operation the flames practically surround the body of the casting 1 and pass upwardly over the portion G' of the generator G. Having generally outlined the construction and operation of the burner, I shall now proceed to 15 describe the essential features of my present invention.

10 designates an ordinary-shaped water-holding tank or reservoir supported in any desired manner outside of the range or heating-stove and at such a place where it can be conveniently filled with water. As shown, the tank 10 has a feed or offtake pipe 11, having a controlling - valve 11^a, which is braced on a bracket-piece 11^b on the pendent 25 pipe-section g, and its end joins with a discharge-nozzle 11^c, which is extended into the bore a and has its outlet of such size as to permit the water to escape in drops, and said nozzle I hereinafter term the "drip-nozzle." 30 The nozzle 11^c extends a short distance into the bore a in a plane above the flame-discharge from the burner, whereby the water is dropped in a direction crossing said flame-discharge or below or on the side of the flame. 35 The pipe 10 may be of any desired metal and is so supported as to be outside of the hot zone of the burner, whereby to act as a simple and inexpensive means for conveying water in drops into the burner-flame at a point 40 outside of the retort or body 1. The water mixing with the gaseous vapor from the burner acts as a resistance to the vapor, and as it diffuses within said vapors it materially aids in loosening the carbon and nitrogen, 45 and, furthermore, by taking up the hydrogen and oxygen a more perfect decomposition of the oily vapors is effected and the odor of the oil completely overcome. Again, the mixture of the aqueous fluid with the gaseous 50 vapors creates a more uniform draft irrespective of the variable flow of the fuel-feed force, and the disagreeable noises incident in

the use of the coal-oil burners of the character stated are thereby greatly reduced.

Having thus described my invention, what 55 I claim, and desire to secure by Letters Patent, is—

1. In combination with a burner of the class described, said burner including a casting having a combustion-chamber comprising a 60 central bore and transverse bores intersecting such central bore, and a vapor-ejector discharging into said central bore, of a water-supply and an offtake-pipe therefor, supported outside of the hot zone of the burner, and 65 including a drip-nozzle projecting into the bore of the casting at a point in a plane above the vapor-ejector and at the same end into which the ejector discharges, whereby to discharge water in the liquid state in drops directly into the combustion - chamber as set forth. 70

2. In a hydrocarbon-burner, a combustion-chamber, having a central longitudinal bore and transverse bores intersecting said central 75 bore, a base, having an extension for said combustion - chamber, said base and extension adapted to hold an absorbent material, a vaporizer mounted over the combustion-chamber and out of contact therewith, a vapor-injector connected to said vaporizer and projecting over said extension to the base, means for injecting water in the combustion-chamber in drops as set forth. 80

3. A hydrocarbon-burner, including a combustion - chamber said combustion - chamber having a longitudinal and transverse bores, and vertical bores extending from the longitudinal and transverse bores to the bottom of the combustion-chamber, a base for said chamber said base adapted to receive absorbent material, a vaporizer arranged above the combustion-chamber in alinement with the longitudinal bore of the chamber, an injector connected with the vaporizer and in alinement 90 with the longitudinal bore from the extension of the base, means for injecting water into the combustion-chamber at the entrant end of the longitudinal bore and in advance of the injector, for the purposes described. 95

OSCAR FALKENWALDE.
